UNITED STATES PATENT OFFICE.

EDWARD H. JEEVES, OF LONDON, ONTARIO, CANADA.

WINDOW-SCREEN ATTACHMENT.

1,120,389.

Specification of Letters Patent.

Patented Dec. 8, 1914.

Application filed September 27, 1913. Serial No. 792,140.

To all whom it may concern:

Be it known that I, EDWARD H. JEEVES, a subject of the King of Great Britain, residing at No. 879 Hellmuth avenue, in the city of London, in the county of Middlesex, Province of Ontario, Dominion of Canada, have invented new and useful Improvements in Window-Screen Attachments, of which the following is a specification.

10 This invention relates to windows and has special reference to an attachment for securing collapsible window screens in place, said attachment being designed to permit the screen to remain attached to the frame of 15 a window ready for use when the window is raised.

The attachment is further designed to permit the moving of the sash into and out 20 of operative relation with the movable sash 20 of a window without removing the screen from the attachment.

The principal object of the invention is to improve and simplify the general construction of device of this character.

25 Another object of the invention is to provide an attachment for window screens that may be readily applied to any size of screen and to any window having sliding sashes, said attachment being so arranged as to permit 30 the ready attachment and detachment of the screen from the window while at the same time securely holding it in position.

With the above and other objects in view the invention consists in general of certain 35 novel details of construction and combination of parts hereinafter fully described, illustrated in the accompanying drawings, and specifically claimed.

In the accompanying drawings, like characters of reference indicate like parts in the 40 several views, and Figure 1 shows a perspective view of a portion of the attachment, the view showing that part which is arranged to be attached to the window frame.

45 Fig. 2 is a perspective view of one end showing the attachment which is secured to the screen in position thereon. Fig. 3 is a transverse section through a window showing the screen in the position in which one of the 50 window sashes is raised so that air is permitted to enter the room where the window is located. Fig. 4 shows the position of the screen when the sash is lowered.

This attachment consists of three separate 55 portions indicated in general by letters A, B and C. Of these three portions the por-

tion A is arranged for attachment to the window frame while the portions B and C are arranged for attachment to the screen at the end thereof. It is to be understood 60 that the portions A, B and C are each duplicated, there being similar portions at each end of the screen and on each side of the sash, and that these duplicated portions are right and left hand in accordance with their 65 position on the frame.

The screen is of the ordinary collapsible variety in which the two sections slide one upon the other and one of these screens is indicated at 10. The end member of such 70 is indicated at 11 and the lower part of the end member is slotted as at 12. Spaced from the bottom of the end member there is provided a second slot 13. The window frame is indicated in general as at 14 and is provided with the usual parting bead 15 and sliding sashes 16 and 17.

The member A consists of a strip of metal bent at right angles to provide a body 18 and a side 19. The side 19 is cut away as 80 at 20 and 21 and the portion 20 which is cut out of the side 19 is bent to project from the part 19 and form a tongue 22. The portion which is cut out at 21 is left attached to the body 18 and bent to form a tongue 23 85 which is provided with a slot 24 at the side adjacent the body 18 so as to form a species of hook. The body 18 is provided with suitable nail holes for the purpose of securing the same to the parting bead 15 at its 90 lower part as shown in Fig. 4.

The member B consists of a plate of metal bent at right angles so as to provide an edge covering portion 25 which extends along the edge of the frame member 11 and 95 a side portion 26 which extends along the side of said member, being secured thereto by suitable nails 27. The edge portion 25 is slotted as at 28, the slot corresponding in size to the slot or recess 12 in the end 100 member 11. This portion 25 is furthermore slotted as at 29 so as to correspond with the slot or recess 13. The slots 28 and 29 correspond in spacing to the tongue 22 and 23 and it is to be noted that the slot 29 is 105 longer than the width of the tongue 22 while the slot 28 is so arranged that when the part A and part B are connected the edge of the slot 28 engages in the slot or recess 24 so that the window screen cannot become 110 accidentally detached from the window frame.

The portion C consists of a body portion 30 which is secured to the edge of the frame member 11 and a tongue 31 which overlaps the side of said frame member and is attached thereto by suitable nails 32. One edge of the portion 30 is provided with a frame portion 33 which is bent at right angles to the portion 30 and extends diagonally with reference to the edge of the frame member 11, the plate from which the member B is made being tapered for this purpose. This diagonal arrangement can clearly be seen in Figs. 2, 3, and 4. The flanges 33 of the portion C are so dimensioned as to bear against the sides of the parting beads 15 when the device is in position.

In use two of the members A, one right and one left are attached to the respective parting beads 15. Similarly two of the members B and two of the members C are attached to the screen 10. The screen is then collapsed and inserted in position in the sash and then expanded so that the tongues 22 enter the respective recesses 13 through the slots 29 while at the same time the tongues 23 are engaged in the recesses 12 through the slots 28. To permit this action the screen is slightly raised above the window sill and when the tongues are thus engaged the screen is dropped, it being understood that the screen is expanded to the full width permitted by the frame in order to permit the engagement of the edge of the slot 28 in the slot 24. It will thus be seen that the lower slot 28 at each end forms a species of pivot in connection with the tongue 33 at said end so that the upper end of the screen is permitted to swing in and out. Now the parts A are so positioned that when the screen swings in at its upper end it will lie beneath the lower edge of the sash 16 and in order to stop the screen from falling too far inward and also to prevent flies and other insects from entering around the edge of said screen the flange 23 is arranged to engage against the sides of the respective stop 15 and thus form a stop flange and closure for the edge portion of the screen.

When it is desired to close the sash 16 it is simply necessary to move the upper end of the screen outward into the position shown in Fig. 4, this being permitted by the working of the tongue 22 loosely in the slot 29 and the pivoting of the tongue 23 in the slot 28. The sash can then be dropped as shown in said figure. When it is desired to remove the screen it is simply necessary to lift the same sufficiently high to permit the edge of the respective member 28 at each

end to clear the tongue 23 when the sash may be collapsed and withdrawn in the usual manner.

There has thus been provided a simple and efficient device of the kind described and of the character specified.

It will be obvious that many minor changes may be made in the form and construction of this invention without departing from the material principles thereof. It is not therefore desired to confine the invention to the exact form herein shown and described, but it is wished to include all such as come properly within the scope claimed.

Having thus described the invention, what is claimed as new, is:—

1. A window screen adapted to be mounted in a window frame having a sliding sash mounted therein, said screen having one edge removably pivoted to said window frame at a location clear of the path of movement of the sash, and arranged to tilt so that the opposite edge may be brought into and out of the path of movement of said sash.

2. A window screen adapted to be mounted in a window frame having a sliding sash mounted therein, said screen having one edge removably pivoted to said window frame at a location clear of the path of movement of the sash, and arranged to tilt so that the opposite edge may be brought into and out of the path of movement of said sash, and coacting stops on said frame and screen arranged to limit the tilting movement of said screen.

3. A window screen adapted to be mounted in a window frame having a sliding sash mounted therein, members at each side of said screen carrying interlocking members, interlocking members carried by said screen and coacting with the first mentioned interlocking members and arranged to pivotally connect one edge of the screen to the frame and permit limited swinging movement of the screen, combined stop and closure members secured to the screen and arranged to engage said members carrying said first mentioned interlocking members when the free edge of the said screen lies in the path of movement of said sash.

In testimony whereof, I have signed in the presence of the two undersigned witnesses.

EDWARD H. JEEVES.
